[57] CLAIM

The ornamental design for a scanner for electronic copying machine, substantially as shown.

DESCRIPTION

FIG. 1 is a front, top and right side perspective view of a scanner for electronic copying machine showing our new design;

FIG. 2 is a perspective view like FIG. 1 with the cover in an open position;

FIG. 3 is a front elevational view thereof;

FIG. 4 is a right side elevational view thereof;

FIG. 5 is a rear elevational view thereof;

FIG. 6 is a left side elevational view thereof;

FIG. 7 is a top plan view thereof;

FIG. 8 is an enlarged top plan view of the operation section with the cover open; and

FIG. 9 is a perspective view thereof, the broken line showing of a copying machine is environmental only and forms no part of the claimed design.
